UNITED STATES PATENT OFFICE.

WILLIAM A. E. HENRICI, OF CHELSEA, MASSACHUSETTS.

DESIGN FOR A LAUNDRY-IRON.

SPECIFICATION forming part of Design No. 25,105, dated January 28, 1896.

Application filed December 26, 1895. Serial No. 573,397. Term of patent 14 years.

To all whom it may concern:

Be it known that I, WILLIAM A. E. HENRICI, of Chelsea, county of Suffolk, and State of Massachusetts, have invented and produced certain new and useful Design for Laundry-irons, of which the following is a specification, reference being had to the accompanying drawings, forming a part thereof.

In the drawings forming part of this specification, Figure 1 is a perspective view, from the rear and one side, of a laundry-iron, showing my design; and Fig. 2 is a similar view taken from the front and side of the iron.

The leading features of my design for a laundry-iron consist in a cylindrical body and a web depending therefrom, terminating

in a flattened foot extended beneath the body. The cylindrical body *a*, shown as hollow or concaved in its top, as at *a'*, has depending therefrom a web *b*, rearwardly and then forwardly curved and terminating in a flattened thin foot *c*, extended beneath the body *a*. 20

What I claim is—

The design for a laundry-iron, substantially as herein shown and described. 25

In testimony whereof I have signed my name to this specification in the presence of two subscribing witnesses.

WILLIAM A. E. HENRICI.

Witnesses:

JOHN COWPER EDUARD,
A. E. DEAN.
